UNITED STATES PATENT OFFICE

GUS EDSTROM, OF MERRILL, WISCONSIN

SCREW DRIVER

Application filed June 26, 1931. Serial No. 547,108.

This invention relates to certain novel improvements in screw drivers, and has for its principal object the provision of an improved construction of this character which will be 5 highly efficient in use and economical in manufacture.

It is the principal object of this invention to provide an improved screw driver, and, more specifically a screw driver in which the 10 driving shank may be continuously rotated in one direction, either clockwise or counter-clockwise, by an oscillating clockwise-counterclockwise motion of the driving means, thereby to eliminate the lost motion associated 15 with the back up movement in screw drivers in which the shank is driven only when the driving means are being rotated in the direction in which the shank is being rotated.

It is another object of the invention to 20 provide unique means for readily changing the direction in which the shank will be rotated by the oscillating clockwise-counter-clockwise motion imparted to the driving means, and to construct these means in such 25 a manner that the screw driver may be readily changed from what will be termed hereinafter "rigid" movement, that is movement of the shank and driving means in the same direction, to either right or left turn rotation 30 of the shank by back and forth movement of the driving means.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is an elevational view of the invention assembled;

Fig. 2 is a longitudinal sectional view on line 2-2 in Fig. 4, showing the operating parts set for clockwise rotation of the shank;

Fig. 3 is a longitudinal sectional view showing the operating parts set for counterclockwise rotation of the shank;

Fig. 4 is a top plan view, partly in section, 50 on line 4-4 in Fig. 3;

Fig. 5 is a sectional view on line 5-5 in Fig. 2;

Fig. 6 is a sectional view on line 6-6 in Fig. 2; and

Fig. 7 is a sectional view on line 7-7 in Fig. 2.

In the drawing, which illustrates a practical and preferred embodiment of the invention, the externally threaded shank of the screw driver is indicated at 10 and has arranged thereon a chuck 11 of conventional design, carrying a removable bit or driver 12. The shank 10 forms one end portion of a shaft 13 on which is mounted, adjacent the shank, and by a pintle 14, a collar 15 that includes a segment 15' in which is provided a slot 16. Formed in the shaft 13 and extending longitudinally or axially thereof, is a keyway or groove 17 in which is slidably mounted a bar 18, the front end of which is notched to provide spaced apart tapered cam faces 19 and 19' which are adapted to be abutted by the periphery of a cam 20 that is loosely mounted on the pintle 14 and provided with a segment of finger-gripping teeth 21. Provided in the front end portion of the slidable bar or rod 18 is a slot 22 through which the pintle 14 projects.

From the above description, therefore, it will now be seen that the bar or rod 18 may be slid in the groove 17, for reasons that will become apparent as the description proceeds, by placing the thumb on the teeth 21 and manipulating the cam wheel 20 against the face 19 of the cam for movement of the bar 18 in one direction, and against cam face 19' for movement of the bar 18 in the opposite direction, while when the cam wheel 20 is disposed as in Fig. 1, the bar 18 is held immovable.

Spaced apart upon and fixed to the shaft 13 are similar collars 23 and 24, each of which is provided with diametrically opposed notches 25, and these collars 23 and 24 are provided with aligned slots 26 through which the slidable bar 18 passes.

Provided in each of the collars 23 and 24 are diametrically opposed slots 27 (Fig. 7). In the slots 27 in collar 24 a pair of latching dogs 28 and 28' are mounted and similar dogs

29 and 29' are mounted in the slots 27 in the collar 23 and each of these dogs 28 and 29 and 28' and 29' is provided with a transversely extending groove 30 through which 5 extends an arm 31 of a link 32—32', each of the links 32 and 32' having one end 33 (Fig. 7) disposed in a recess 34 in the slide bar 18 and the other end 34a (Fig. 4) hooked under a pin 35 that protrudes from the collar (23 or 24).

15 Associated with each of the collars 23 and 24 is a substantially semi-circular spring 36 and each of which springs is disposed in one of the notches 25 in the collars, and the ends 37 of these springs are directed through slots 38 in the latching dogs 28 and 28', and 29 and 29'. The springs 36 tend, therefore, to spread the pairs of dogs 28 and 28' and 29 and 29' apart and to lift them out of the 20 slots 27 in the collars 23 and 24.

25 Apertured for the passage therethrough of the shaft 13 is a block 39 which is fixed to the immovable sleeve 43 at 44 and which floats on shaft 13. This block 39 carries diametrically opposed studs 40 on each of which is rotatably mounted a bevel gear 42. One end of the stationary sleeve 43 is attached to this block 39 by screw 44, and the other end of the stationary sleeve 43 is attached, by 30 screw 45, to a block 46 that rides loosely on the shaft 13 and is slotted for the passage therethrough of the slide bar 18.

35 The sleeve or hand grip 47 has its rear end attached, by screw 48, to a bearing block 49 in which the rear end of shaft 13 is journaled, while the front end of the sleeve 47 is attached, by screw 50, to a bevel gear 51 that is rotatably mounted on shaft 13 and meshes with the bevel gears 42. The bevel gear 51 40 is provided with a ring of spaced latching fingers 52 which extend over a part of the collar 24 and into the spaces between which the latching dogs 28 and 28' may be spread in a manner to be explained hereinafter.

45 In front of the bevel gears 42, meshing therewith, and rotatably mounted on the shaft 13, is a bevel gear 53 that is similar to gear 51 and that has a ring of latching fingers 54 that are similar to the fingers 52, and into the spaces between which fingers 54 the latching dogs 29 and 29' may be spread 50 by movement of the slide bar 18 in a manner to be described presently.

55 The latching dogs 29 and 29' have oppositely beveled edges 55 and 56 (Fig. 6) and the dogs 28 and 28' are similarly constructed.

60 The operation of the invention is as follows: Assuming that the operator desires to employ the device as a rigid screw driver and to drive the shaft 13, its shank 10 and bit 12 continuously in a right or left turn (clockwise or counterclockwise rotation) by a similar movement of sleeve 47, he then moves the cam wheel 20 into the position of Fig. 1

which will, acting through the slide bar 18, raise the links 32 in the slots 30, and allow the springs 36 to spread the latching dogs 28—28' and 29—29' apart, thus disposing dogs 29 and 29' between fingers 54 and dogs 28 and 28' between fingers 52. It is therefore readily apparent that rotation then imparted to sleeve 47 will rotate the entire device as a rigid unit since the gear 51 to which the sleeve 47 is attached, by screw 50, cannot then be rotated independently of the shaft 13 to drive the bevel gears 42 and its companion gear 53; this by reason of the straight or non-beveled edges 57 and 58 of dogs 29 and 29' and corresponding edges on dogs 28 and 28' which will be abutted by the fingers 54 and 53 when the motion of sleeve 47 is imparted to gear 51.

When it is desired to rotate shaft 13, its shank 10 and bit 12 continuously in a right 55 turn or clockwise rotation, as seen looking from right to left in the drawing, the cam wheel 20 is moved into the position of Fig. 2 which moves the slide bar 18 forward and raises the links 32' in slots 30 so that the 60 dogs 28 and 29 are moved by springs 36 into spaces between adjacent pairs of fingers 52 and 54, respectively, while withdrawing the dogs 28' and 29' into their respective slots 27 in the collars 24 and 23 respectively, by means of links 32 which are eccentric with respect to links 32'. The sleeve 43 being held

65 in one hand, the to and fro, or oscillatory driving movement then imparted by the operator's other hand to sleeve 47 will be transmitted, through screw 50 to gear 51, and as the gear 51 is rotated counterclockwise (looking from right to left in the drawing) the fingers 52 will ride over the beveled edge of dog 28, which is beveled in the opposite direction to the bevel 55 of dog 29, and motion will then be imparted by gear 51 to gears 42, and gear 53. The gear 53, shaft 13, and bit 12 will thus be rotated clockwise, since one

70 of the fingers 54 will abut the edge 57 of dog 29, imparting motion through the dog 29 to collar 23 and the shaft 13. When the operator reverses the movement of sleeve 47 and rotates sleeve 47 to the right, (clockwise

75 as seen looking from right to left in the drawing) the motion imparted by sleeve 47 to gear 51 will be transmitted through gears 42 to gear 53 which will then be rotated counterclockwise (looking from right to left in the drawing) and the fingers 54 will then

80 ride over the beveled edge 55 of dog 29 while one of the fingers 52 will abut the edge (corresponding to edge 57 of dog 29) of dog 28

85 which will rotate collar 24 and shaft 13 in a right turn or clockwise direction, thus translating the to and fro wrist movement imparted to sleeve 47 into a continuous right

88 turn or clockwise rotation of shaft 13 and bit 12.

When it is desired to translate the to and 120

fro or oscillatory wrist movement imparted to sleeve 47 into a continuous left turn or counterclockwise rotation of shaft 13 and bit 12, the operator moves cam wheel 20 into 5 the position of Fig. 3, and thereby slides bar 18 rearwardly. This rearward movement of slide bar 18 raises links 32 in their respective slots 30 while withdrawing the links 32' into their slots 30 and the dogs 28 and 10 29 into their respective slots 27 in the collars 24 and 23, thereby allowing the springs 36 to move the dogs 28' and 29' out beyond the peripheries of the collars 24 and 23. Therefore, when sleeve 47 is rotated to the right 15 (clockwise as seen looking from right to left in the drawing) motion will be imparted by sleeve 47 to gear 51, to gears 42, which will rotate gear 53 to the left (counterclockwise), the fingers 52 then riding over the beveled 20 edge (corresponding to beveled edge 56 of dog 29') of dog 28', while one of the fingers 54 abuts the edge 58 of dog 29' and thereby rotates the dog 29', collar 23, shaft 13 and bit 12 to the left (counterclockwise). When 25 the operator reverses the rotation of sleeve 47 and rotates this sleeve to the left (counterclockwise looking from right to left in the drawing) the motion of sleeve 47 is imparted to gear 51, to gears 42, to gear 53 which is 30 thus rotated clockwise, and the fingers 54 of gear 53 will then ride over the beveled edge 56 of dog 29', while one of the fingers 52 of gear 51 will abut the non-beveled or straight edge (corresponding to edge 57 of dog 29') 35 of dog 28' so that the leftward (counterclockwise) motion of gear 51 will be transmitted through dog 28' to collar 24, and to shaft 13, and bit 12 which will thus be rotated continuously in a left turn or counterclockwise direction, as seen looking from right to left in 40 the drawing.

From the foregoing description it will therefore be apparent that the invention provides unique, simple, and conveniently operated means for translating the oscillatory or to and fro wrist motion imparted to a screw driver selectively into either a continuous right turn or left turn rotation of the driver shaft and bit, while being so arranged that the device may be used as a rigid screw driver when so desired.

While I have illustrated and described the preferred form of construction for carrying my invention into effect, this is capable of 5 variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A tool of the character described com-

prising a rotative shaft, spaced members on and fixed to the shaft, a driving gear and a driven gear floating on the shaft, a slide bar, spaced elements on said gears projecting over the collars, latching elements on each of the first-named members, elements on 70 said gears projecting over the first-named members and engageable with said latching elements to latch the gears to the first-named members, and means including elements having connection with the slide bar for 75 moving said latching elements into and out of latching engagement with the projecting elements on said gears.

2. A tool of the character described comprising a rotative shaft, a pair of spaced collars on and fixed to the shaft, a driving gear and a driven gear floating on the shaft, a slide bar, spaced elements on said gears projecting over the collars, latching elements on each of said collars movable into latching 80 engagement with said projecting elements to latch the gears to the collars, springs urging said latching elements into latching engagement with said projecting elements, and means having connection with the slide bar 85 for moving said pivotal elements out of latching engagement with said projecting elements against the action of said springs.

3. A tool of the character described comprising a rotative shaft, a pair of spaced collars on and fixed to the shaft, a driving gear and a driven gear floating on the shaft, a slide bar, spaced elements on said gears projecting over the collars, a pair of latching elements on each of said collars movable 90 into latching engagement with said projecting elements to latch the gears to the collars, each of said latching elements having a beveled edge and a straight edge, springs urging 95 said latching elements into latching engagement with said projecting elements, and means having connection with the slide bar for moving simultaneously one of said pivotal elements from each pair thereof out of latching engagement with said projecting 100 elements against the action of said springs, whereby the projecting elements on the gears when rotated in one direction will ride over the beveled edge of said latching elements but will engage the straight edges thereof 105 when rotated in the opposite direction and thereby latch the collars to the gears.

4. A tool of the character described comprising a rotative shaft, a pair of spaced collars on and fixed to the shaft, a driving gear 120 and a driven gear floating on the shaft, a slide bar, spaced elements on said gears projecting over the collars, a pair of latching elements on each of said collars movable into latching engagement with said projecting 125 elements to latch the gears to the collars, each of said latching elements having a beveled edge and a straight edge, springs urging said latching elements into latching engagement with said projecting elements, and links hav-

ing connection with the slide bar for moving simultaneously one of said pivotal elements from each pair thereof out of latching engagement with said projecting elements against the action of said springs, whereby the projecting elements on the gears when rotated in one direction will ride over the beveled edges of said latching elements but will engage the straight edges thereof when rotated in the opposite direction and thereby latch the collars to the gears.

In testimony whereof I affix my signature.
GUS EDSTROM.
